APPARATUS FOR DRILLING DEVIATING
BORES UTILIZING A PLURALITY OF
CURVED TUBULAR DRILL GUIDE SEC-
TIONS

John A. Zublin, Los Angeles, Calif.

Application November 6, 1951, Serial No. 255,026

3 Claims. (Cl. 255—1.6)

1

The present invention relates to apparatus for drilling lateral bores which deviate from existing vertical well bores.

According to the present invention the drill bit is carried at the lower end of the flexible drill string section and the short, curved drill guide sections are positioned above the bit. The assembly can be lowered into the well with the curved drill guide sections in positions which cause them to impart reverse curvature to the flexible drill string section. The overall lateral dimensions of the apparatus are thus limited and no difficulty is encountered in lowering the assembly into an existing well bore. A whipstock is positioned within the existing well bore at the location at which it is desired for the lateral bore to deviate from the existing bore. This whipstock may be lowered into the well individually in advance of the drilling assembly or it may be lowered simultaneously therewith. The whipstock is provided with a curved guideway through which the curved drill guide sections pass. This curved guideway serves to initially force the drill bit laterally into the wall of the existing well bore to begin the drilling of the lateral bore. As the drilling proceeds the curved guideway of the whipstock causes the curved drill guide sections to assume relative positions which impart a substantially continuous curve to the flexible drill string section. The curved lateral bore which is thus drilled prevents the curved drill guide sections from relative rotation and the substantially continuous curve of the flexible drill string section is thus maintained during drilling. It will thus be seen that for practical purposes I obtain a rigid, continuously curved drill guide for that part of the flexible drill string section which has passed through the whipstock. This advantageous result is obtained while still providing an assembly which can be easily lowered into the existing well bore.

The primary purpose of this invention is to provide a drilling assembly for lateral bores which can be easily and rapidly lowered into an existing well bore and which provides a rigid, continuously curved guide for the drill bit during drilling of the lateral bore. Another object of the invention is to limit the overall lateral dimensions of an assembly for drilling lateral bores during the lowering of that assembly into an existing well bore. Still another object of the invention is to provide a flexible drill string section and a rigid guide therefor in combination with a whipstock which is capable of controlling or altering the configuration of the rigid drill

2

guide at the point of deviation of the lateral bore in the well. Further objects and advantages of the invention will be understood by reference to the following description taken in connection with the accompanying drawing, wherein:

Figure 1 is a view partly in side elevation and partly in longitudinal section of an assembly which embodies the present invention and which is positioned in a well; and,

Figure 2 is a fragmentary view similar to Figure 1, but illustrating the apparatus in position for lowering into a well and prior to initiation of drilling of a lateral bore.

The reference numerals 3 and 4 designate tubular sections of a heavy duty flexible drill pipe of the type described and claimed in my Patent No. 2,515,366. The tubular section 4 is secured at its lower end by means of a dovetail tongue and slot connection 5 to a spindle 6 having a tubular passageway 7 therethrough. The shank 8 of the spindle 6 is received within the upper end of a short, rigid, tubular, curved drill guide section 9. The shank 8 is provided with anti-friction ball bearings 10 and 11 to reduce the friction between this shank and the drill guide section 9. I also prefer to provide some suitable form of packing 12 to prevent leakage of drilling fluids.

A double-ended spindle 13 has its upper shank 14 journaled in the lower end of the drill guide section 9 and its lower shank 15 journaled in the upper end of a second tubular, curved, rigid drill guide section 16. The upper shank 14 may be provided with suitable ball bearings 17 and 18 and with a packing 19. The lower shank 16 may be similarly provided with anti-friction ball bearings 20 and 21 and with a packing 22.

A bit spindle 23 is provided with a shank 24 which is journaled in the lower end of the drill guide section 16. The shank 24 is provided with suitable ball bearings 25 and 26 and with a suitable packing 27. A drill bit 28 is threaded securely at 29 to the lower end of the spindle 23.

The ball bearings 10, 11, 17, 18, 20, 21, 25 and 26 serve to reduce friction and also act as thrust bearings which prevent longitudinal separation of the elements with which the bearings are associated.

It will be noted that the construction of the tubular drill guide sections 9 and 16 is such that the spindles which are received within the upper and lower ends thereof must always lie at an angle to each other. When the drill guide sections 9 and 16 occupy the relative positions illustrated in Figure 2, a reverse curvature, as shown,

is imparted to the flexible drill string section which consists of the members 3, 4, 6, 13 and 23. When, however, the tubular drill guide sections 9 and 16 are rotated through 180° relative to each other, they occupy the positions shown in Figure 1 and they impart a substantially continuous curvature to the flexible drill string section. It should here be pointed out that the shank 8 of the spindle 6 is provided with an enlarged keyway 30 which loosely receives a key 31 on the upper end of the shank 14 of the spindle 13. Similarly, the lower end of the spindle 15 of the shank 13 is provided with an enlarged keyway 32 which loosely receives a key 33 on the upper end of the spindle 23. Power can thus be supplied to the drill bit 28 from the rigid drill pipe 34 positioned above the upper tubular section 3 of the flexible drill string section.

A whipstock is provided for changing the configuration of the drill guide portion of the apparatus from the configuration shown in Figure 2 to that shown in Figure 1 after the assembly has been lowered into the well to the point at which it is desired to drill the laterally deviating bore. The whipstock is designated generally by the reference numeral 35 and it is provided with a suitable supporting foot 36 which rests on the bottom of the hole and a standard 37 of suitable length to position the upper end of the whipstock in the desired position longitudinally of the hole. The main body 38 of the whipstock is provided with a curved guideway 39 which functions in the manner hereinafter described. The main body portion 38 is provided at its upper end with a collar 40. I deem it preferable to lower the whipstock into the well together with the other elements of the assembly illustrated in the drawing. For this purpose the collar 40 of the whipstock is positioned around the spindle 23 and the lower end of the tubular drill guide section 16 in the manner illustrated in Figure 2. A shearable bolt 41 may be used to hold the elements thus assembled.

The assembly is arranged and positioned as illustrated in Figure 2 during lowering into the existing well bore 42. The whipstock is properly oriented to cause the guideway 39 to deflect the drill bit into the azimuth in which it is desired to drill the lateral bore. When the foot 36 of the whipstock reaches the hole bottom, the weight of the assembly above the whipstock will cause the bolt 41 to shear which will permit the flexible drill string and the drill guide sections to be lowered through the collar 40 and along the curved guideway 39. This curved guideway will cause the drill bit to be deflected laterally to initiate drilling of the lateral bore 43. The drill guide section 16, if it is not already in appropriate position, will be caused to rotate to assume a position to follow the curvature of the guideway 39. The guideway 39 and the curved drill guide section 16 cause the drill bit 28 to follow a curved path during the drilling of the first portion of the lateral bore 43. The curved drill guide section 9 will eventually pass through the collar 40 and will enter the curved guideway 39. This drill guide section 9 will also be caused to rotate to assume a position which follows the curvature of the guideway 39. At the same time the portion of the curved lateral bore which has already been drilled will be preventing rotation of the drill guide section 16. The drill guide section 9 will eventually enter the curved lateral bore 43 and rotation of this drill guide section will also be

prevented by the curvature of the lateral bore. The curved drill guide sections 9 and 16 will thus be prevented from rotating relative to each other within the curved lateral bore. It will be appreciated that the drill guide sections 9 and 16, together with the spindles 13 and 23 will thus provide a curved, rigid guide for the drill bit while those elements are positioned in the curved lateral bore.

I have illustrated and described apparatus which includes only the two curved drill guide sections 9 and 16. It is possible to increase the number of such drill guide sections and this may be found advisable in some instances. It will be apparent that the portion of the flexible drill string section which is above the curved drill guides and which is illustrated as consisting of the tubular sections 3 and 4 may be made of greater length by simply increasing the number of such sections. The length of the lateral bore 43 may be made as long as desirable by thus providing sufficient length of the flexible drill string.

The apparatus may be withdrawn from the well by merely elevating the drill pipe 34. The portions of the apparatus which have entered the lateral bore 43 will first be withdrawn from that bore. After the curved drill guide sections 9 and 16 have passed upwardly through the curved drill guide 39, gravity will cause the assembly to assume the configuration illustrated in Figure 2, thus reducing the overall lateral dimensions of the assembly. The bit 28 will engage the lower edge of the collar 40 and the whipstock will thus also be withdrawn from the well.

I have illustrated and described what I now consider to be a preferred embodiment of the present invention. It is to be understood, however, that the illustrated and described embodiment is exemplary only, and that various alterations and modifications may be resorted to without departing from the broader scope of the invention as defined by the following claims.

Having thus described my invention, I claim:

1. Apparatus for drilling a lateral bore deviating from an existing vertical well bore comprising a flexible, non-resilient drill string section, a drill bit secured to the lower end of and rotatable with said flexible drill string section, a plurality of relatively short independent rigid curved tubular drill guide sections mounted for independent rotation on said flexible drill string section, said drill guide sections when disposed in one relative position of rotation holding said flexible drill string section in a succession of reversed curves and when moved to another relative position of rotation holding said flexible drill string section in a substantially continuous curve and a whipstock over which said curved drill guide sections may pass to insure their being brought from said first relative position of rotation to said latter relative position of rotation.

2. Apparatus for drilling a lateral bore deviating from an existing vertical well bore comprising a flexible, non-resilient drill string section embracing a plurality of interconnected metallic units, a drill bit secured to the lower end of and rotatable with said flexible drill string section, a plurality of relatively short independent rigid curved tubular drill guide sections mounted for independent rotation on said flexible drill string section, each of said curved guide sections surrounding portions of at least two of

said metallic units, said drill guide sections when disposed in one relative position of rotation holding said flexible drill string section in a succession of reversed curves and when moved to another relative position of rotation holding said flexible drill string section in a substantially continuous curve and a whip-stock over which said curved drill guide sections may pass to insure their being brought from said first relative position of rotation to said latter relative position of rotation.

3. Apparatus for drilling a lateral bore deviating from an existing vertical well bore comprising a flexible, non-resilient drill string section, a drill bit secured to the lower end of and rotatable with said flexible drill string section, a plurality of relatively short independent rigid curved tubular drill guide sections mounted for independent rotation on said flexible drill string section, means on said flexible drill string sec-
